LISTENING-KEY CIRCUITS.

1,260,413.

Specification of Letters Patent. Patented Mar. 26, 1918.

Application filed October 25, 1916. Serial No. 127,667.

To all whom it may concern:

Be it known that we, ALBEN E. LUNDELL and FRANKLIN A. STEARN, citizens of the United States, residing, respectively, at 5 New York, in the county of Bronx and State of New York, and Paterson, in the county of Passaic and State of New Jersey, have invented certain new and useful Improvements in Listening-Key Circuits, of 10 which the following is a full, clear, concise, and exact description.

This invention relates to telephone exchange systems employing operators, and more particularly to improvements in operator's listening-key circuits.

It is the object of this invention to provide means whereby an operator may listen from one cord to another at a high rate of speed.

20 A feature of the invention is a double wound relay controlling a second relay, at whose contacts connection between its cord and the operator's head-set may be made. When the operator's head set is to be connected to another cord, the high resistance locking circuit of the first relay will be shunted out by the low resistance operating winding of the corresponding relay associated with the second cord.

30 It is thought that the invention will be best understood from the following detailed description, reference being had to the accompanying drawing.

In the drawing, the answering end of a 35 connecting operator's cord circuit is diagrammatically shown at the left, while at the right is shown a portion of the circuit of a second cord at the same operator's position.

40 Assuming that the position is idle and that a call comes in over the line terminating in jack 1, the operator will be informed in the well-known manner by the lighting of the usual line lamp (not shown). She then inserts plug 2 into jack 1, whereupon a circuit will be completed for relay 3, from ground, winding of relay 3, sleeve contacts of plug 2 and jack 1, to grounded battery through the winding of the well-known 50 cutoff relay (not shown). Relay 3, at its outer armature, completes a circuit from ground, outer armature and front contact of relay 3, left-hand armature and back contact of relay 4, left-hand winding of

relay 5, armature and back contact of relay 6, and resistance 7 to grounded battery. 55 Relay 5 attracts its armatures, completing a circuit from ground, left-hand armature and front contact of relay 5, winding of relay 9 to grounded battery. 60

Relay 9 attracts its armatures and completes a circuit at its right-hand armature from ground, connecting cord sequence switch contact 10, right-hand armature and front contact of relay 9, winding of the 65 power magnet 11 of the connecting cord sequence switch to grounded battery. The connecting cord sequence switch moves from position 1 into position 2, under the control of its normal spring 12. 70

In position 2 of the connecting cord sequence switch a circuit is completed from grounded battery, sequence switch contact 13, left-hand armature and front contact of relay 9 and the winding of relay 4 to 75 ground. Relay 4 is energized and locks up over a circuit from ground, winding of relay 4, right-hand armature and front contact of relay 4, inner armature and front contact of relay 3 to grounded battery. 80

The operation of relay 4 allows a circuit, previously shunted out through its back contact, to be completed from grounded battery, resistance 7, armature and back contact of relay 6, right and left-hand 85 windings of relay 5 in series, winding of relay 8, right-hand armature and front contact of relay 5 to ground. Relays 5 and 8 are locked up in this circuit.

As soon as relay 8 attracts its armature, 90 the connecting operator may converse with the calling subscriber and ascertain the number of the wanted line. If no further connections are desired, she "listens-out" by depressing listening-out key 14, whereupon relay 6 is energized and opens the circuit through relays 5 and 8, whereupon they deenergize and disconnect the operator's head-set from the cord. 95

If the operator, before depressing the 100 listening-out key, inserts a second plug into an answering jack, the operation of relay 5' associated with such second cord will shunt out relay 5, since the circuit through relay 5' is at this time only through its 105 low-resistance left-hand winding. Relay 5', upon actuation, locks itself to ground in a manner similar to that of relay 5, and ener-

gizes a relay corresponding to relay 8 to connect the operator with the second cord.

Assuming now that the operator has listened-in on her second cord, and again desires to listen-in on the first cord, she depresses listening-in key 15, whereupon a circuit will be closed from grounded battery, resistance 7, armature and back contact of relay 6, low-resistance left-hand winding of relay 5, armature and front contact of relay 4, which remains locked up as long as plug 2 remains in jack 1, to ground, through the contacts of key 15. The low resistance winding of relay 5 in turn shunts out the high resistance locking circuit through the two windings of relay 5'.

It is to be noted that only momentary depression of listening key 15 is required, since the relay 5 locks itself up as soon as it is actuated.

What is claimed is:

1. In a telephone exchange system, a plurality of subscribers' lines, a plurality of link circuits for interconnecting said lines, an operator's head set, a plurality of relays, there being one of said relays per link circuit to control the connection of said head set to said link circuits, an energizing circuit completed for one of said relays as a result of the extension of a line to the link circuit with which such relay is associated, means for deenergizing said relay simultaneously with the energization of a second one of said relays, and a manually operable key to control the reenergization of a previously actuated one of said relays.

2. In a telephone exchange system, a plurality of subscribers' lines, a plurality of link circuits for interconnecting said lines, an operator's head set, a plurality of relays, there being one per link circuit to control the connection of said head set to said link circuits, energizing circuits for said relays, locking circuits for said relays, alternate means for completing said energizing circuits, and means for rendering a locking circuit ineffective whenever an energizing circuit is completed.

3. In a telephone exchange system, a plurality of subscribers' lines, a plurality of link circuits for interconnecting said lines, an operator's head set, a plurality of double wound relays, there being one per link circuit, to control the connection of said head set to said link circuits, energizing circuits extending through one winding of said relays, locking circuits for said relays extend-

ing through both of their windings in series, alternate means for completing said energizing circuits, and means for shunting out 60 a locking circuit whenever an energizing circuit is completed.

4. In a telephone exchange system, a plurality of subscribers' lines, a plurality of link circuits for interconnecting said lines, 65 an operator's head set, a plurality of relays, there being one per link circuit to control the connection of said head set to said link circuits, energizing circuits for said relays, locking circuits for said relays, a manually 70 operable key, means for completing said energizing circuits either upon momentary depression of said key or upon extension of a line to a link circuit, and means for rendering a locking circuit ineffective whenever 75 an energizing circuit is completed.

5. In a telephone exchange system, a plurality of subscribers' lines, a plurality of link circuits for interconnecting said lines, 80 a double wound relay for each of said link circuits, a second relay to establish connection between said head set and its associated link circuit, and energizing circuit for said first relay extending through one 85 winding only, a locking circuit for said first relay extending through its windings in series and including the winding of said second relay, a manually operable key, and means to complete said energizing circuit either in response to operation of said key 90 or in response to the extension of a calling line to a link circuit, and means for shunting out a locking circuit whenever an energizing circuit is completed.

6. In a telephone exchange system, a plurality of subscribers' lines, a plurality of link circuits for interconnecting said lines, an operator's head set, relays, one for each link circuit, to control the connection of said head set to said link circuits, energizing 100 circuits for said relays, locking circuits for said relays, a manually operable key individual to each of said link circuits, means for completing an energizing circuit for the relay of a link circuit either upon extension 105 of a line to said link circuit or upon depression of the key corresponding to said link circuit, and means for opening any existing locking circuit whenever an energizing circuit is completed.

In witness whereof, we subscribe our names this 24th day of October, A. D., 1916.

ALBEN E. LUNDELL.

FRANKLIN A. STEARN.
